COMBINED COMB AND BOTTLE OPENER

Alfred F. Greene, P.O. Box 402, Sanford, Fla. 32771

Filed Nov. 6, 1972, Ser. No. 304,037

Term of patent 14 years

Int. Cl. D28—03; D7—06

U.S. Cl. D86—8

Fig. 2.

Fig. 1.

Fig. 3.

FIG. 1 is a side elevational view of a combined comb and bottle opener showing my new design, the opposite side being a mirror image thereof;

FIG. 2 is a front elevational view; and

FIG. 3 is a rear elevational view.

I claim:

The ornamental design for a combined comb and bottle opener, as shown and described.
